UNITED STATES PATENT OFFICE.

FRED W. RAUSKOLB, OF MEDFORD, MASSACHUSETTS.

MOUNTING FOR GOLD-LEAF.

1,163,222.

Specification of Letters Patent. Patented July 14, 1914.

Application filed April 17, 1913. Serial No. 761,857.

To all whom it may concern:

Be it known that I, FRED W. RAUSKOLB, a citizen of the United States of America, and a resident of Medford, in the county of 5 Middlesex and State of Massachusetts, have invented certain new and useful Improvements in Mountings for Gold-Leaf, of which the following is a specification.

This invention relates to mounting for 10 metal leaf and particularly gold leaf, the particular object of the present invention being to provide a mounting which can be readily handled and which may be used without the necessity of applying sizing to 15 the leather or other material to which the leaf is to be affixed. Heretofore in affixing gold leaf and other metal leaves to leather and other material it has become necessary to apply to the material a sizing 20 and then overlay the sizing with a layer of metal leaf, after which the necessary characters are affixed to the material by means 25 of a heated die. By that method not only is the material disfigured by having the sizing affixed thereto, but much time is consumed by the operator in doing this, and more time is consumed in removing the surplus leaf from the material after the desired 30 impression has been made. When this metal leaf is gold the portion lost in its removal from the sized material is of considerable value. Where the ordinary gold leaf is applied to sized material great care has to be exercised to keep the metal layer flat 35 and free from wrinkles.

The present invention consists in providing 40 a new article of manufacture that will overcome these objections, said article consisting of a sheet of gold leaf with a backing of nonadhesive paper applied thereto by pressure and provided on the opposite face thereof with a fine coating of adhesive sizing.

The invention further consists in certain 45 novel features of construction and arrangement of parts which will be fully understood by reference to the description of the drawings and to the claims hereinafter given.

50 Of the drawings: Figure 1 represents a sheet of paper. Fig. 2 represents a sheet of metal foil. Fig. 3 represents a sheet of paper having the sheet of metal foil spread thereover. Fig. 4 represents, in diagram

greatly enlarged, the edges of a sheet of paper, a sheet of metal foil superimposed thereon, and a sheet of prepared paper superimposed upon said metal foil. Fig. 5 represents a sheet of the prepared paper having a sheet of metal foil affixed thereto by pressure, and showing in the upper left hand corner a coating of sizing applied thereto. Fig. 6 represents an enlarged reverse view of a portion of the sheet of prepared paper having the metal foil affixed thereto, and showing its condition after a plurality of characters have been removed therefrom by means of a heated die, and Fig. 7 represents a portion of a book showing thereon a plurality of characters in metal leaf removed from said sheet of metal leaf and affixed thereto.

Similar characters designate like parts throughout the several figures of the drawings.

In the drawings, 10 represents a sheet of paper such as is ordinarily used upon which to spread the sheet of metal foil 11. In the preparation of the improved mounting a sheet of metal foil 11 is spread upon one 80 of the sheets of paper 10 and then a sheet of previously prepared paper 12 is superimposed thereon as indicated in Fig. 4 of the drawings. This sheet of paper 12 is preferably treated to a paraffin bath so that it is 85 transparent. The three sheets are then subjected to pressure so that the sheet of metal foil 11 will adhere firmly to the sheet of paraffin paper 12 and will be spread smoothly thereover. While only one series 90 of sheets 10, 11, and 12 are shown in Fig. 4, it is obvious that in practice a plurality of these series of sheets will be formed in a pile and subjected to pressure simultaneously. After the pressure has been applied 95 the sheets of paraffin paper 12 are removed from the pile, each of these sheets having adhering thereto a sheet of metal foil 11, and the sheets 10 are removed therefrom. The whole face of the metal foil 11 and that 100 portion of the sheet of the paraffin paper 12 exposed is treated to a spray of suitable sizing material as shown at 13 in the upper left hand corner of Fig. 5. This sizing material may be of any suitable composition 105 that will remain impervious to moisture and is adapted to be brought into a tacky condition only when subjected to intense heat.

These mountings when thus prepared are ready for the market and adapted for use when desired.

When it is desired to apply characters to leather or other material the sheet of metal leaf is laid upon the material and a heated die having the necessary characters thereon is quickly applied to the rear face of the sheet of paraffin paper. Owing to the transparency of this sheet 12 it is possible to work closely to the edges of the sheet of metal leaf and also to other characters which have been previously removed therefrom. This application of the heated die will affect only that portion of the sizing directly opposite the characters upon the die and will cause that portion of the metal leaf to be firmly fixed to the leather or other material. When this has been accomplished the sheet 20 is removed from the material and all of the metal leaf upon the sheet of paraffin paper 12 will be removed therewith except that portion thereof which has been fixed to the material by the action of the heated die.

25 When the mounting has been used several times the appearance of the mounting will be similar to that indicated in Fig. 6 of the drawings, and the appearance of the leather or other material to which the metal leaf has 30 been applied will be similar to that shown in Fig. 7 of the drawings with no disfigurement about the characters of sizing, such as is usually found when the characters have been applied in the usual manner.

35 It is obvious that by means of this mounting it is unnecessary to cut up the sheets of metal foil into small pieces as has been customary, and by this means much waste of material is obviated. Moreover, all the 40 metal leaf not used remains affixed to the sheet of paraffin paper, and when the entire surface of the mounting has been utilized these sheets are accumulated and burnt and

the metal remaining thereon is thereby saved and may be returned to the manufacturer 45 to be formed into new sheets of metal foil.

The coating of sizing on the gold leaf is very thin and of only sufficient quantity to cause the gold to adhere to an article when a heated die is applied. As a consequence, 50 when the heated die is applied and the sizing opposite the raised portions becomes tacky there is not enough substance thereto to permit it to spread beyond the outlines of the characters on the die and a much 55 more perfect imprint is assured as a result.

Another advantage of this improved article of manufacture is that the workman is not bothered with keeping the leaf flat as has been the case heretofore when no backing was provided for the sheet. Moreover, in the application of the gold leaf a great saving of time is assured by the use of the improved sheet.

It is believed that the many advantages 65 of this improved article of manufacture will be fully understood from the foregoing description.

Having thus described my invention, I claim:

1. As a new article of manufacture, a sheet of gold leaf having a backing of paper on one face and a coating of adhesive sizing applied directly to its other face.

2. As a new article of manufacture, a 75 sheet of gold leaf having a backing of transparent paper on one face and a coating of adhesive sizing applied directly to its other face.

Signed by me at 4 Post Office Square, Boston, Mass., this 12th day of April, 1913.

FRED W. RAUSKOLB.
